US00D800675S

(12) **United States Design Patent** (10) **Patent No.:** **US D800,675 S**
(45) **Date of Patent:** **** Oct. 24, 2017**

(54) **SET OF COOLING PLATE ROWS FOR IN-LINE MEMORY**

(71) Applicant: **Asetek Danmark A/S**, Aalborg East (DK)

(72) Inventors: **Torben Søgaard Schaltz**, Hobro (DK); **Jan Hunskjær**, Svenstrup (DK); **Kim Henriksen**, Tylstrup (DK)

(73) Assignee: **Asetek Danmark A/S**, Aalborg East (DK)

(**) Term: **15 Years**

(21) Appl. No.: **29/565,778**

(22) Filed: **May 24, 2016**

(51) LOC (10) Cl. **13-03**

(52) U.S. Cl.

USPC **D13/179**

(58) **Field of Classification Search**

(57) **CLAIM**

The ornamental design for a set of cooling plate rows for in-line memory, as shown and described.

DESCRIPTION

FIG. 1 is a top front right perspective view of a set of cooling plate rows for in-line memory showing our new design;

FIG. 2 is a top rear left perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof; and,

FIG. 8 is a left side elevation view thereof.

The dash-dash broken lines shown in the drawings illustrate portions of the set of cooling plate rows that form no part of the claimed design.

1 Claim, 5 Drawing Sheets
